UNITED STATES PATENT OFFICE

158,626

STOCKING

Wilhelmina Tait, Wyomissing, Pa., assignor to Millway Knitting Mills, Inc., Millway, Pa., a corporation of Pennsylvania

Application May 18, 1949, Serial No. 2,722

Term of patent 14 years

(Cl. D47—7)

To all whom it may concern:

Be it known that I, Wilhelmina Tait, a citizen of the United States, residing at Wyomissing, Pennsylvania, have invented a new, original, and ornamental Design for a Stocking, of which the following is a specification, reference being had to the accompanying drawing, form part thereof.

Fig. 1 is a reduced side elevational view of a stocking embodying my new design.

Fig. 2 is an enlarged side elevational view of the lower portion of a stocking embodying my new design.

Fig. 3 is an enlarged rear elevational view of the same.

I claim:

The ornamental design for a stocking, as shown.

WILHELMINA TAIT.
